MIRROR OR THE LIKE

Richard M. Chapin, Charlotte, N.C., assignor to C. B. Atkin Company, Knoxville, Tenn., a corporation of Tennessee

Filed Oct. 14, 1968, Ser. No. 13,976

Term of patent 3½ years

Int. Cl. D6—06

U.S. Cl. D33—9

The back of the mirror is substantially plain and unornamented.

I claim:

The ornamental design for a mirror or the like, substantially as shown and described.
